UNITED STATES PATENT OFFICE.

BENJAMIN JUDD ABBOTT, OF CHICAGO, ILLINOIS, ASSIGNOR TO CHARLES H. DURPHY, OF SAME PLACE.

ANNEALING-FURNACE.

SPECIFICATION forming part of Letters Patent No. 593,557, dated November 16, 1897.

Application filed April 5, 1897. Serial No. 630,700. (No model.)

To all whom it may concern:

Be it known that I, BENJAMIN JUDD ABBOTT, a citizen of the United States, residing in Chicago, in the county of Cook and State of Illinois, have invented a new and useful Improvement in Annealing-Furnaces, of which the following is a specification.

My invention relates to improvements in annealing-furnaces.

10 The object of my invention is to provide a furnace or apparatus of a simple, durable, and efficient construction by which metal articles may be rapidly and cheaply annealed, while at the same time a regular and uniform annealing action is imparted to each and every article and a uniform product thus turned out.

20 My invention consists, essentially, in the combination, with a heating-furnace, of an inclined rotating annealing chamber or cylinder through which the articles to be annealed are conveyed or pass in connection with hot sand, with which the articles to be annealed come in contact as they pass through the cylinder—in at one end and out at the other. It 25 also consists, in connection with these parts, in an elevator or conveyer for returning the sand over and over again to the rotating annealing chamber or cylinder, in a screen for 30 separating the sand from the annealed articles, and in a supplemental rotating chamber or cylinder for reheating the sand as it is conveyed back to the annealing chamber or cylinder, so that the sand may be kept of a 35 comparatively uniform temperature while acting upon the articles to be annealed.

40 My invention further consists in the novel construction of parts and devices and in the novel combinations of parts and devices herein shown and described, and specified in the claims.

45 In the accompanying drawings, which form a part of this specification, Figure 1 is a vertical longitudinal section of an annealing furnace or apparatus embodying my invention. Fig. 2 is a cross-section on the line 2 2 of Fig.

50 1. Fig. 3 is a detail plan view of the screen and discharge-chute for separating the sand from the annealed articles. Fig. 4 is a detail end view showing one of the adjustable bearings for the shaft of the rotating chamber or cylinder.

In the drawings, A represents the fire-box of a furnace, A' its heating-chamber, and A² its smoke flue or stack.

55 The furnace may be of any suitable kind or construction and designed for burning any suitable kind of fuel. In the drawings I have illustrated it as being furnished with a grate A³ for burning coal.

60 B is an inclined rotating annealing-chamber, preferably of cylindrical form, extending longitudinally across the heating-chamber of the furnace, through which the hot sand C and the articles to be annealed are 65 conveyed or pass, and B' is the similar rotating cylinder or chamber for reheating the sand as it is returned to the rotating annealing chamber or cylinder B.

65 The cylinder B is open at both ends for 70 admission and discharge of the sand and articles to be annealed, and it is provided with short or stub shafts b, secured thereto by winged heads or spiders b', which fit inside the cylinder and are bolted or riveted thereto. The shafts b b are journaled in adjustable boxes b² b², fixed to the framework E by adjusting-screws b³ b³. The upper or supplemental cylinder is likewise open at both 75 ends for admission and discharge of the sand and has similar short shafts or gudgeons b, spiders b', journal-boxes b², and adjusting-screws b³. The journal-box at the lower end of the cylinder B is mounted in an adjustable collar or plate b⁴, fixed to the frame E 80 by adjusting-screws b⁵.

85 D is an elevator or conveyer for lifting the hot sand from the boot or pit D', into which it is discharged from the cylinder B, and delivering it into the upper end of the rotating cylinder B', through the chute or spout D², with which the elevator is provided for this purpose.

90 The elevator or conveyer D may be of any suitable kind or construction, but preferably 95 consists of a chain d, running over pulleys furnished with buckets d² and inclosed in a case d³.

100 F is a screen by which the articles annealed are separated from the sand as the same are delivered together from the annealing-cylinder B, and F' a chute for delivering the annealed articles into the car G or other convenient receptacle.

H is the chute or spout for carrying the hot sand from the reheating cylinder or chamber B' into the annealing-cylinder B, and H' is a spout or chute for delivering the articles to be annealed into the cylinder B from the receiving platform or hopper H², onto which they may be dumped from the car or conveyer H³.

The annealing-cylinder B and the sand-reheating cylinder B' are both continuously rotated by any suitable gearing or mechanism.

As illustrated in the drawings, M is the driving-shaft, furnished with a driving-pulley M' and having a gear m meshing with an intermediate gear m' on a counter-shaft m², and which meshes with a gear m³ on the reheating-cylinder B'. The lower cylinder B is driven from the cylinder B' through a gear m⁴ on the cylinder B, which meshes with said gear m³ on the cylinder B'.

20 The driving-shaft M is provided with a gear m⁵, which meshes with a gear m⁶ on the upper pulley-shaft d⁴ of the elevator D.

To receive the end thrust of the inclined rotating cylinders B B', the shaft b at the lower end of each is provided with a hardened-steel bearing toe b⁶, which bears against the bearing-disks b⁷ b⁷ in the journal-boxes b² of said shafts.

In operation the attendant standing in the pit N feeds or pushes the articles to be annealed along the delivery-chute H' into the rotating inclined annealing chamber or cylinder B, which is partially filled with hot sand C and into which the reheated sand is being

35 constantly delivered or returned from the cylinder B'. Owing to the inclination and rotation of the cylinder B, the sand and articles to be annealed are slowly fed or conveyed through the same from one end to the other,

40 and as the articles are thus conveyed through the annealing-chamber they are heated to a uniform degree by reason of the hot sand and the tumbling, stirring, or mixing action produced by the rotation of the cylinder and the

45 uniform time required for passing the articles through the cylinder. As the sand and heated articles are discharged from the lower end of the cylinder B the same pass onto the screen F, which separates the sand from the articles,

50 the articles passing along the chute F' to the car G and the sand dropping into the pit or boot D' of the elevator. The elevator or conductor D then returns the sand to the rotating inclined sand-reheating cylinder B', through which the sand then slowly passes

55 back to the receiving end of the cylinder B, into which it is delivered by the spout or chute H. The operation is thus continuous and automatic and uniform upon each and every article.

As illustrated in Fig. 2 the wall of the furnace projects out or approaches close to the cylinder B' at a and close to the cylinder B' at a', so as to properly deflect the flame or heated

65 products of combustion around and against the cylinders and heat the same. This I con-

sider to be the preferable construction of the furnace.

I claim—

1. In an annealing apparatus, the combination with a furnace of an inclined rotating annealing chamber or cylinder for passing or conveying sand and the articles to be annealed through or across the furnace, and means for returning the sand again and again to said rotating annealing chamber or cylinder, substantially as specified.

2. In an annealing apparatus, the combination with a furnace of an inclined rotating annealing chamber or cylinder for passing or conveying sand and the articles to be annealed through or across the furnace, means for returning the sand again and again to said rotating annealing chamber or cylinder, and means for reheating the sand as it is being returned to said annealing chamber or cylinder, substantially as specified.

3. In an annealing apparatus, the combination with a furnace of an inclined rotating annealing-chamber or cylinder, an oppositely-inclined rotating sand-reheating chamber or cylinder, a screen for separating the sand from the articles being annealed, and an elevator or conveyer for delivering the sand into said reheating chamber or cylinder, substantially as specified.

4. In an annealing apparatus, the combination with a furnace of an inclined rotating annealing chamber or cylinder, an oppositely-inclined rotating sand-reheating chamber or cylinder, a screen for separating the sand from the articles being annealed, an elevator or conveyer for delivering the sand into said reheating chamber or cylinder, and a chute or spout for returning the sand from said reheating chamber or cylinder to said annealing chamber or cylinder, substantially as specified.

5. In an annealing apparatus, the combination with a furnace of an inclined rotating annealing chamber or cylinder, an oppositely-inclined rotating sand-reheating chamber or cylinder, a screen for separating the sand from the articles being annealed, an elevator or conveyer for delivering the sand into said reheating chamber or cylinder, a chute or spout for returning the sand from said reheating chamber or cylinder to said annealing chamber or cylinder, a discharge-chute for the annealed articles and a delivery-chute for the same, substantially as specified.

6. In an annealing apparatus, the combination with a furnace of a rotating annealing-chamber extending across the heating-chamber of the furnace, and means for causing sand to be repeatedly returned to and passed through said chamber with the articles to be annealed, substantially as specified.

BENJAMIN JUDD ABBOTT.
